UNITED STATES PATENT OFFICE.

CHARLES E. HEYER, OF CHICAGO, ILLINOIS, ASSIGNOR TO BARNHART BROS. & SPINDLER, OF SAME PLACE.

DESIGN FOR A FONT OF PRINTING-TYPE.

SPECIFICATION forming part of Design No. 22,999, dated January 2, 1894.

Application filed June 19, 1893. Serial No. 478,173. Term of patent 14 years.

To all whom it may concern:

Be it known that I, CHARLES E. HEYER, a citizen of the United States, residing at Chicago, county of Cook, and State of Illinois, have 5 invented and produced a new and original Design for a Font of Printing-Type, which is fully set forth in the following specification, reference being had to the accompanying drawings, forming a part thereof.

- The font embodying this design comprises upper and lower case letters, Arabic numerals, character "&," abbreviation, "Co.," dollar mark and points. All the letters and characters are moderately heavy faced, without hair-lines. The lower case letters are moderately condensed. All terminal lines, of both upper and lower case letters, are finished with ceriphs which, in the case of the stems are slight, being no more than a swelling of the end of the line by flaring the corners sharply, but not broadly. The ceriphs, however, upon the terminals of curved or horizontal strokes are very marked and are unsymmetrical, the point of the ceriph inward with respect to the letter (whether that be upward or downward) being very acutely tapered and thereby elongated, the opposite point being an angle which is barely acute, and in some instances scarcely less than a right angle. The upper end of lower case f, the lower end of lower case t, the characteristic of lower case r, and both the terminals of the horizontal strokes of lower case z illustrate this feature which may be seen in many other places. The same characteristic appears in the upper case letters, the slant strokes following the rule stated as to vertical strokes, as seen in capitals A, W, V, X, and other places; and the characteristic stated as to horizontal or curved strokes is seen in both terminals of capital C, the terminals, both of upper and lower strokes of capitals E, F and L. The characteristic or middle

stroke of capitals A, E and F is an exception to the rule as to horizontal strokes, said strokes 45 following the rules stated as to vertical stems. Lower case g has its characteristic or tail marked with the feature above described as to the ceriph of horizontal or curved strokes, at the end where it makes junction with the 50 upper end of the letter, the junction consisting in mere proximity of the upper point of the ceriph to the upper or oval element of the letter. The upper terminal of this letter is almost imperceptibly swelled and obliquely 55 sharpened in imitation of a ceriph. The middle or characteristic stroke of capitals E and F, and the cross stroke of capital H, are considerably above the height of said letters respectively, and to correspond with this feature, the oval of capital P and R, and the upper oval of capital B, are much less than half the height of the letter, and the junction of the lower slant stroke of capital K with the letter is also above the middle; and the oblique strokes of capital Y and the crossing of the strokes of capital X are at the same 60 level above the middle of the height of the letters respectively. To harmonize with this characteristic, the capital W has its two intermediate strokes meeting at an angle considerably below the top of the letter, and about at the level of the junction of the oblique strokes of capital Y and the bottom of the ovals of P, B and R; and this point or 65 level is approximately the level of the top of the lower case letters which do not extend 70 above the line.

I claim—

The design for a font of type herein shown 80 and described.

Chicago, Illinois, June 5, 1893.

CHARLES E. HEYER.
